DEVICE FOR FINGER NAILS

Eugene C. Rohrbach, Ridgewood, N. J.

Application September 5, 1934, Serial No. 742,755

14 Claims. (Cl. 63—2)

This invention relates to devices adapted to be mounted on finger nails so that they overlie the outer surfaces thereof and the principal object of the invention is to provide a simply constructed

device of this character that can be readily attached to the finger nail without the use of cementitious material and will firmly adhere to the finger nail during usage. Another object of the invention is to provide a device of the indicated type that can be readily and easily mounted on or removed from the finger nail without injury to the finger nail and which, when in position on the finger nail, will prevent injury to the tip portion of the latter. A further object of the invention is to provide a detachable finger nail device having a covering portion which will protectively overlie the outer surface of the finger nail and may be colored or decorated to suit the taste of the user thereof.

Other objects and advantages as well as the novel details of construction of this invention will become apparent after a consideration of the description hereinbelow set forth, taken in connection with the accompanying drawing in which Fig. 1 is a perspective view of a hand showing the manner in which the devices constructed in accordance with the invention are mounted on the finger nails; Fig. 2 is a top view of a finger having a device constructed according to one embodiment of the invention mounted thereon; Fig. 3 is an enlarged top view of the device shown in Fig. 2; Fig. 4 is a side elevation of the device looking from the right of Fig. 3; Fig. 5 is a sectional view taken on the line 5—5 of Fig. 3; Fig. 6 is a top view of a modified form of the invention and Fig. 7 is a plan view showing the under side of the device illustrated in Fig. 6.

Referring more particularly to the drawing wherein like reference characters designate corresponding parts throughout the several views, the numeral 10 designates generally a finger of the hand illustrated having a natural finger nail 11, the tip portion of which is shaped and extends beyond the outer end of the finger 10 in the usual manner.

Mounted on the tip portion of the finger nail 11 is a device made in accordance with the invention and generally designated by the numeral 12. The device 12 comprises an upper or covering portion 13, adapted to overlie the outer surface of the tip portion of the finger nail 11 and an under portion 14 adapted to be positioned under the tip portion of the finger nail, the upper and lower portions 13 and 14, respectively, co-operating to detachably hold the device securely

in place on the tip of the finger nail without injury to the latter, as will be hereinafter more fully explained.

The covering portion 13 is formed substantially in the shape of a crescent so as to conform to the shape of the tip portion of a finger nail which has been manicured or shaped to the usual form, the inner end portion 15 of the covering 13 being curved so as to conform to the inner edge of the tip portion of the finger nail and the outer end portion thereof having converging edges 16 so as to provide a relatively pointed end portion 17, corresponding to the outer end of the tip portion of the finger nail 11, the inner ends of the edge portions 16 meeting with the ends 15 of the inner edge portion 15 to form the inwardly extending portions 18. The body portion of the covering 13 is curved in transverse section in varying degree so as to snugly fit against the outer surface of the tip portion of the nail. As shown more clearly in Figs. 4 and 5, the converging edges 16, and end portion 17 and the inner end portions 18 all lie substantially in the same plane, the body portion of the covering 13 gradually curving away from these portions of the plane and having its greatest distance therefrom at a point situated substantially midway on the inner edge portion 15 thereof. It will thus be evident, that the covering portion 13 of the device is similar in form to the tip portion of a finger nail which is shaped in the usual manner and when the device is in position on the finger nail will snugly overlie and completely cover the tip portion thereof, the inwardly extending portions 18 preferably tapering off to the sides of the finger nail. In those cases where the tip of the finger nail is not pointed the end portion 17 formed by the converging edges 16 will of course be eliminated, the edges 16 in that case forming a continuously curved edge. It is also within the contemplation of the invention to have the covering 13 shaped to conform to the configuration of the entire finger nail so that when the device is mounted on the nail, the covering portion will entirely cover the outer surface of the finger nail.

The covering portion 13 may be made of any material having sufficient rigidity so that the covering portion will maintain its shape during usage. I preferably make the covering portion 13 of metal such as tin, brass, silver, gold, etc., which has been cut, stamped or otherwise formed to the shape desired. The covering portion may also be coated, as by paint or enamel, or have decorative work thereon or may be used as a setting.

for precious or semi-precious stones, glass, etc.

The under portion 14 of the device which is adapted to fit snugly against the under surface of the tip portion of the nail is formed substantially similar to the covering portion 13, the inner end 19 thereof being curved so as to conform to the natural contours of the inner end section of the tip portion of the finger nail where it is attached to the outer end of the finger, and the outer edges 20 of the under portion 14 being shaped similar to and substantially flush with the outer edge portions 16 of the covering 13. The outer edges 20 of the under portion 14 and the edges 16 of the covering 13 are soldered or otherwise securely fastened together. The degree of curvature of the body portion of the under side 14 is slightly less than that of the covering 13 so that a crescent-shaped slit or opening is provided within which the tip portion of the finger nail may be inserted. Due to the fact that the spacing between the covering 13 and the under side 14 gradually narrows down towards the outer edges of the device, as clearly shown in Figs. 4 and 5, it will be seen that when the device is pushed on the tip portion of the finger nail, the forward edge of the latter will wedge between the covering 13 and the under side 14, whereby the device is securely held in position on the finger nail. As will be noted from Figs. 4 and 5 of the drawing, the underside 14 is relatively thinner than the covering 13 so that as the finger nail is inserted in position in the device the under side 14 will tend to give without deforming the covering 13. The under side 14 is made of a material having sufficient resiliency so that when it is pushed away from the covering 13 by the inserted nail, it will be placed under tension and bear tightly up against the under side of the tip portion of the finger nail. To obtain the desired spring or fastening result I preferably make the under side 14 of relatively thin metallic material, although other materials may be used to equal advantage. It will be thus seen from the above description that the device can be readily and easily attached to or removed from the tip portion of the finger nail and while mounted thereon will be securely held to the tip portion of the finger nail without any danger of falling off during usage.

In the embodiment shown in Figs. 6 and 7 of the drawing, the covering portion 25 is provided with an integral inwardly extending flange 28 on the under side thereof, which forms a support for the flexible under portion 29. This construction is assembled by slidably inserting the under portion 29 in position, after which the flange 28 may be crimped to securely and permanently hold the under portion 29 in place. In the modified construction illustrated in these figures, the covering 25 is provided with an inwardly extending portion 26 which extends over the outer surface of the finger nail. This extension tends to enable the device to obtain a firmer grip on the finger nail, thereby lessening the chances of its being knocked off during usage and also gives a desirable decorative effect. To enhance this decorative effect, precious or semi-precious stones 27 may be set in the covering portion and extension 26, as illustrated.

It is, of course, understood that various other changes and modifications may be made in the details of construction and design of the invention without departing from the spirit thereof, hence I do not wish to limit myself strictly to the specific constructions above described.

I claim:

1. A device adapted to be mounted on a natural finger nail comprising a covering portion adapted to overlie the outer surface of a finger nail and being curved in transverse section so as to snugly engage therewith, and an under portion adapted to be inserted under the tip of the finger nail, said under portion being relatively more flexible than said covering portion and being so secured to the latter that when inserted under a finger nail, it is placed under a tension sufficient to cause it to tightly engage with the under surface of the finger nail and to detachably hold the covering portion in place upon the outer surface of the finger nail.

2. A device adapted to be mounted on a natural finger nail comprising a substantially crescent-shaped covering section adapted to overlie the outer surface of a portion of a finger nail and a similarly shaped section adapted to be inserted under the tip of the finger nail, the outer curved edges of said covering section and said under section being secured together so that a substantially wedge-shaped space is formed therebetween.

3. A device adapted to be mounted on a natural finger nail comprising a covering section adapted to snugly overlie the outer surface of a finger nail and an under section secured to said covering section at its side edges and adapted to be inserted under a finger nail, said under section being so formed relative to said covering section that it is placed under tension when the device is inserted on a finger nail and engages the under side of the tip portion of said finger nail with sufficient pressure to hold the device securely in position on the finger nail.

4. A device adapted to be mounted on a natural finger nail comprising a covering section adapted to snugly overlie the outer surface of a finger nail and means adapted to frictionally engage the under side of the tip portion of said finger nail for detachably securing the device to the finger nail, said means comprising a substantially crescent-shaped member having relatively greater flexibility than said covering section and being so secured to the latter that when inserted under a finger nail, it is placed under a tension sufficient to cause it to tightly engage with the under surface of the finger nail.

5. A device adapted to be mounted on a natural finger nail comprising a covering section adapted to snugly overlie the outer surface of the finger nail, decorative material carried on the outer surface of said covering section, and means adapted to frictionally engage the under side of the tip portion of the finger nail for detachably securing the device to the finger nail, said means comprising a plate having greater flexibility than said covering section and secured to said covering section in such manner that a transversely curved space having tapering edges is formed therebetween.

6. A device adapted to be mounted on a natural finger nail, comprising a covering section adapted to snugly overlie the outer surface of a finger nail and composed of relatively stiff material, and a flexible under section secured to said covering section and adapted to frictionally engage the under side of the tip portion of said nail for removably securing said device to the finger nail, said covering section and said under section being so formed relative to each other that when a finger nail is inserted in the device, the

outer edge portion of the finger nail is wedged therebetween.

7. A device such as set forth in claim 6 in which said upper covering section and said under section are formed substantially in the shape of the tip portion of the finger nail.

8. A device adapted to be mounted on a natural finger nail comprising a substantially crescent-shaped covering section adapted to overlie the outer surface of the tip portion of the finger nail, and a similarly shaped section adapted to be inserted under the tip of the finger nail, said covering section and said under section being curved in transverse section so as to snugly engage with the upper and under surfaces, respectively, of the tip portion of the finger nail and being secured together at the outer edge portions thereof so that the outer edge portion of a finger nail will be wedged therebetween.

9. A device adapted to be mounted on a natural finger nail, comprising a covering section adapted to snugly overlie the outer surface of a finger nail and composed of relatively stiff material, an inwardly extending flange provided on the under side of the outer edge portion of said covering section, and a relatively flexible under section supported in inwardly flexed condition between said covering section and said flange, said under section being adapted to yieldingly resist insertion of the device on a finger nail and to tightly engage with the under surface of the finger nail when the device is in position thereon.

10. A device adapted to be mounted on a natural finger nail, comprising a substantially crescent-shaped covering section adapted to overlie the outer surface of the tip portion of a finger nail, and a similarly shaped section secured to said covering section and adapted to be inserted under the tip of the finger nail, said covering section and said under section being curved in transverse section so as to snugly engage with the upper and under surfaces, respectively, of the tip portion of the finger nail, the transversely curved space between said sections gradually increasing in thickness toward the rear thereof, so that when the tip portion of the nail is inserted in the device, the forward portion thereof will be wedged between said sections.

11. A device adapted to be mounted on a natural finger nail, comprising a substantially crescent-shaped covering section adapted to overlie the outer surface of the tip portion of a finger nail, and a similarly shaped section secured to said covering section and adapted to be inserted under the tip of the finger nail, said covering section and said under section being curved in

transverse section so as to snugly engage with the upper and under surfaces, respectively, of the tip portion of the finger nail, the degree of curvature of the covering section being increasingly greater than that of the under section, so that a wedge-shaped space is formed between such sections.

12. A device adapted to be mounted on a natural finger nail, comprising a covering section adapted to overlie the outer surface of a natural finger nail, and an under section secured to said covering section and adapted to be inserted under the tip of the finger nail, said covering section and said under section being curved in transverse section so as to snugly engage with the upper and under surfaces, respectively, of the tip portion of the finger nail, the transversely curved space between such sections having greater thickness at the rear edge portions of said sections than at the forward edge portions thereof, so that the finger nail will be wedged therebetween.

13. A device adapted to be mounted on a natural finger nail, comprising a covering section adapted to overlie the outer surface of a natural finger nail, and an under section secured at its outer edge portions to the outer edge portions of said covering section and adapted to be inserted under the tip of the finger nail, said covering section and said under section being both longitudinally and transversely curved, the degree of transverse curvature of that portion of the covering section which lies directly above the rear end portion of said under section, being substantially greater than that of the latter.

14. A device adapted to be mounted on a natural finger nail, comprising a relatively rigid covering section, adapted to overlie the outer surface of a natural finger nail, and an under section secured at its outer edge portion to the outer edge portion of said covering section and adapted to be inserted under the tip of the finger nail, said under section being relatively more flexible than said covering section and adapted to tightly engage with the under surface of the finger nail when the device is inserted thereon, said covering section and said under section being so formed relative to each other that a transversely curved tapering space is formed therebetween, the degree of transverse curvature of that portion of the covering section which lies directly above the rear end portion of said under section being substantially greater than that of the latter.

EUGENE C. ROHRBACH. 55
